R. O. LOUGHEED

AUXILIARY AIR VALVE FOR AUTOMOBILES

Filed July 31, 1922

FIG. 3.

FIG. 2.

INVENTOR

Randle O. Lougheed
by
Owen, Owen & Hampton

UNITED STATES PATENT OFFICE.

RANDLE O. LOUGHEED, OF MONTPELIER, OHIO.

AUXILIARY AIR VALVE FOR AUTOMOBILES.

Application filed July 31, 1922. Serial No. 578,543.

To all whom it may concern:

Be it known that I, RANDLE O. LOUGHEED, a citizen of the United States, and a resident of Montpelier, county of Williams, and State of Ohio, have made an invention appertaining to an Auxiliary Air Valve for Automobiles; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 My invention has for its object to provide an automatic auxiliary air intake for automobile engines whereby the auxiliary air will not be admitted to the engine unless the engine has been sufficiently heated to cause 20 the fuel to be heated sufficiently to warrant the admission of air through the automatic auxiliary valve. It also provides in combination with the automatic control, a valve having a certain weight for the purpose of 25 closing the valve or springs of a certain tension for the same purpose whereby opening of the valve will be prevented, notwithstanding the temperature to which the engine may be raised by its previous operations 30 until the engine is operated at a certain speed to cause a certain amount of suction or to produce a certain predetermined vacuous condition in the intake manifold of the engine.

35 A further object of my invention is to provide a very narrow opening between two heated surfaces through which the auxiliary air will pass upon its entrance into the engine and be heated.

40 The invention also has for its object other advantages and features which will appear from the following description and from an examination of the drawings.

The invention may be contained in structures of different forms. To illustrate a practical application of the invention, I have selected a structure embodying the invention and shall describe it hereinafter. The structure selected is illustrated in the 50 accompanying drawings.

Fig. 1 of the drawings is a conventional view of the intake and exhaust manifold of an internal combustion engine commonly used in automobiles showing the structure embodying my invention in operative relation to the engine and the manifold. Fig.

2 is a sectional view of a part of the device embodying my invention. Fig. 3 is a sectional view of a part of the device illustrated in Fig. 2.

In Figure 1, 1 is the exhaust manifold. 2 is the intake manifold. The manifolds are held by means of clamps 3 in a manner well known in the art. A part of the device embodying my invention is secured in 60 close proximity to the exhaust manifold and to the engine head by means of two of the clamps 3 that extend over a flange or a pair of projections 4 that are formed integral with the device, and thus the device is 65 clamped in position in close proximity to the parts that are heated in the operation of the engine.

The flange 4 forms a part of a cup 5. The cup 5 is closed by a flanged cover 6. 70 The flange 7 of the cover, however, is located on the inside of the cup. It is of comparatively considerable width and thus extends from the edge of the cup to well within the cup. The cover 6 and flange 7 75 is formed integral and is formed of one kind of a metal while the cup 5 is formed of another kind of metal. The expansivity, therefore, of the two is dissimilar and the coefficient of expansion of the metal of the 80 cover is less than the coefficient of the metal of the cup. When, therefore, the cup and its cover is comparatively cold, that is, substantially at atmospheric temperature, the cover tightly fits the cup so as to completely 85 close the end of the cup. When, however, the cup and cover are heated during the operation of the engine, the cup expands more than the cover expands, with the result that a very narrow opening is formed 90 between the flange 7 and the edge portion of the cup as shown somewhat enlarged in Fig. 3. This narrow annular space of considerable length will heat any air that is drawn through the crack that is thus formed 95 between the cover and the cup to near the temperature of the cover and the cup.

A pipe 8 is located within the cup and passes through the bottom or end of the cup to the intake manifold of the engine, preferably at a point well below the arms of the intake manifold. One end of the pipe 8 is provided with a ball valve 9 that it seated by means of a spring 10. The ball valve and the spring 10 are located in a thimble 11 that is secured to the end of the pipe 8 such as by press fit or by thread. The

spring 10 has such a tension as to hold the ball 9 seated until the suction produced by the engine, that is, until the vacuous condition within the intake manifold is of such a degree as to cause the atmospheric pressure to force the valve open and consequently the admission of air into the intake manifold through the pipe 8. The air, however, will not be admitted unless the temperature of the engine has been raised by preceding operations of the engine sufficiently to cause the cup to be opened by the thermostatic relation between the cover and the cup. This insures that no auxiliary air will enter into the engine unless the conditions are such that it will be heated at least as high as a predetermined temperature.

Ordinarily the auxiliary air will be heated sufficiently by the intimate relation of the air with the heated parts of the device produced by the exceedingly narrow passageway formed between the flange of the cover and the edge portion of the cup, but if it is desired to further heat the air it may be done by extending the length of that portion of the pipe 8 located within the cup. The pipe 8 may be coiled in order that it may be contained within the cup.

I claim:

1. In an automatic auxiliary air valve for an internal combustion engine, a cup connected with the intake manifold of the engine, a cover substantially fitting the interior of the cup, the cup and cover formed of material having dissimilar expansivity to close and open the cup according to the temperature of the cup and cover.

2. In an automatic auxiliary air valve for an internal combustion engine, a cup connected with the intake manifold of the engine, a cover having a flange substantially fitting the interior of the cup, the cup and cover formed of material having dissimilar expansivity to close and open the cup according to the temperature of the cup and cover, a flange and the edge portion of the cup forming a narrow slit for causing intimate contact with the air entering the manifold through the cup to raise the temperature of the air substantially to that of the cup and cover.

3. An automatic auxiliary air valve for an internal combustion engine and having a passageway communicating with the intake manifold of the engine, thermostatic

elements for closing and opening the passageway until the temperature of the said valve has been raised to a predetermined degree, a spring pressed valve for maintaining the passageway closed until the vacuous condition of the intake manifold has reached a predetermined degree.

4. An automatic auxiliary air valve for an internal combustion engine, comprising a pair of members having normally contacting surfaces and formed of material having dissimilar thermal expansivity, one of the members having a passageway communicating with the intake manifold of the engine, the members operating to close and open the passageway according to the temperature of the members, a spring pressed valve for maintaining the passageway closed until the vacuous condition of the intake manifold has reached a predetermined degree.

5. In an automatic auxiliary air valve for an internal combustion engine, a cup connected with the intake manifold of the engine, a cover substantially fitting the interior of the cup, the cup and cover formed of material having dissimilar expansivity to close and open the cup according to the temperature of the cup and cover, a spring pressed valve for maintaining the connection of the cup with the intake manifold closed until the vacuous condition of the intake manifold has reached a predetermined degree.

6. In an automatic auxiliary air valve for an internal combustion engine, a cup connected with the intake manifold of the engine, a cover having a flange substantially fitting the interior of the cup, the cup and cover formed of material having dissimilar expansivity to close and open the cup according to the temperature of the cup and cover, a flange and the edge portion of the cup forming a narrow slit for causing intimate contact with the air entering the manifold through the cup to raise the temperature of the air substantially to that of the cup and cover, a spring pressed valve for maintaining the connection of the cup with the intake manifold closed until the vacuous condition of the intake manifold has reached a predetermined degree.

In testimony whereof I have hereunto signed my name to this specification.

RANDLE O. LOUGHEED.
